GEAR-OPERATED PANCAKE-TYPE WRENCH
FOR USE IN CONFINED SPACESFrank J. De Note, Forestville, Conn., assignor to

Application January 6, 1951, Serial No. 204,773

1 Claim. (Cl. 81—57)

1

This invention relates to automatic wrenches, and is more particularly directed to improvements in power driven socket wrenches for use in tightening or loosening nuts situated in places that are either inaccessible, or difficult to reach with ordinary wrench tools.

One object of this invention is to provide a power driven socket wrench having an angularly off-set nut-engaging member which is substantially free from interfering mechanisms so that it may be used in uniformly tightening or loosening nuts or bolts about which there is a minimum of clearance from surrounding structures.

Another object of this invention is to provide a device of the character described which has an off-set nut-engaging member at the remote end of an elongated barrel housing so that the wrench may be used to operate on nuts located in deep, confined recesses, such as are encountered in the assembly of cylinder heads in radial aircraft engines.

A further object is to provide a device of the above nature which will be simple in construction, inexpensive to manufacture, easy to manipulate, compact, and very efficient and durable in use.

With these and other objects in view there has been illustrated on the accompanying drawing one form in which the invention may conveniently be embodied in practice.

In the drawings,

Fig. 1 shows in two parts, the invention as applied to a motor-driven, trigger-actuated power tool, and further illustrates its adaptability for operation on a nut in the closely confined space between two cylinders of a radial aircraft engine, as represented by the dashed lines.

Fig. 2 is a top view of the off-set nut-engaging drive mechanism, partly in section, taken along the broken line 2—2 of Fig. 1, looking in the direction of the arrows.

Fig. 3 is a sectional view of the same, taken along the line 3—3 of Fig. 1.

Fig. 4 is a bottom view of the off-set nut-engaging drive mechanism taken along the line 4—4 of Fig. 1.

Fig. 5 is a side view of the hexagonally rounded end of the drive shaft.

Fig. 6 is an end view of the same.

Fig. 7 is a side view, partly in section, of the shaft barrel housing, showing the lower sleeve bearing in place therein, and further showing how the end of the barrel is fixed in angular relationship to the rear cover of the socket drive mechanism.

2

Referring now to the drawings, in which like reference numerals denote corresponding parts throughout the several views, the numeral 10 indicates generally a trigger-actuated tool embodying the invention.

The tool 10 includes an air-driven slip clutch C having a rotative drive member 11 provided with an hexagonal central socket 11a within which is disposed the hexagonal end portion 12 of an elongated drive shaft 13. The drive shaft 13 is rotatably disposed within an elongated barrel housing 14, for which purpose said barrel housing has a pair of sleeve bearings 15 and 16, one disposed within either end thereof. The barrel housing 14 is held in fixed aligned relationship to the casing of the tool 10, by a split tubular housing member 17, tightly secured in place by means of a clamping screw 18 within one side thereof.

The outer lower end of the elongated drive shaft 13 is provided with a hexagonal oval-shaped pointed head 19, adapted to be received within a hexagonal central opening 20 in an externally-toothed drive gear 21, driven by said drive shaft 13.

The drive gear 21 is provided with an annular shoulder 22 of reduced diameter, rotatably seated within a replaceable bushing 36 located at the inner end of a gear housing body 23, the latter being provided with a centrally located stepped pin 24 on which is rotatably disposed an idler gear 25, in meshing engagement with the drive gear 21. At the outer end of the gear housing body 23, there is rotatably disposed an externally-toothed wrench socket 26, having a plurality of internal nut engaging faces 27. The wrench socket 26 is also provided with an annular shoulder 28, of reduced diameter, embraced by the gear housing body 23, the outer end of said gear housing body 23 comprising merely a thin arcuate band 29. The arcuate band 29 could form part of a replaceable ring 37 fixed in the housing body 23 as by spot welding 38.

The outer end of the elongated barrel housing 14 has a rear cover member 30 fixed to it, as by a circumferential weld 31, and disposed in inclined relationship thereto. The rear cover member 30 is detachably fixed to the gear housing body 23 as by means of a pair of machine screws 32.

The front cover member 33 is similarly detachably fixed to the gear housing body 23 by a pair of machine screws 34, the purpose of said front cover member being to retain the idler gear 25 and the externally toothed socket 26 in operating position within the housing body 23. The front

cover member 33 is provided with a pair of forwardly-extending ear portions 35 overlaying the rearward half of the externally-toothed socket 26.

Operation

The operation of the improved socket wrench can readily be understood by referring to Fig. 1 of the drawing. Thus it will be seen that the toothed wrench socket 26, being unincumbered at the outer end of the gear housing body 23, may readily be placed over a nut or bolt to be turned. The fact that the housing portion holding the socket at its outer end consists merely of the thin band 29 of the ring 37 allows the improved tool to be used in cases where the nut to be operated upon is closely adjacent a side wall.

When the trigger T is pressed, the clutch C will operate to continuously rotate the drive shaft 13 until the nut is tightened to a predetermined torque, after which the clutch C will slip and prevent damage to the parts. The tool will then be removed from the nut and applied to the next nut on the engine cylinder. To remove the nut, the drive shaft 13 will be operated in the reverse direction, under the control of a rotary reversing switch knob S.

Although the particular embodiment herein described shows the wrench socket 26 disposed at a certain angle with respect to the elongated barrel housing 14, it is to be understood that this angle may be varied considerably, within the spirit and scope of the invention, to suit the particular job to be done.

One advantage of the improved wrench herein disclosed is that it is capable of operating on nuts or bolts in small restricted areas.

Another advantage is that the improved tool is very small in size and light in weight, therefore making it ideal for assembly line production.

While there has been disclosed in this specification one form in which the invention may be

embodied, it is to be understood that this form is shown for the purpose of illustration only, and that the invention is not to be limited to the specific disclosure, but may be modified and embodied in various other forms without departing from its spirit. In short, the invention includes all the modifications and embodiments coming within the scope of the following claim.

Having thus fully described the invention, what is claimed as new, and for which it is desired to secure Letters Patent, is:

In an offset socket wrench, a substantially rectangular, pancake-type housing open at one end and having rotatably mounted therein in meshing engagement with each other a wrench socket gear whose periphery extends through the open end of the housing, a driver gear, and an intermediate idler gear, the outer periphery of the wrench socket gear having a concentric circular recess disposed in the bottom portion thereof, a thin metal band of substantially the thickness of the teeth of the wrench socket gear mounted in said circular recess, and constituting the sole closure means for the open end of the housing, thereby adapting the wrench to use on nuts or bolts located in very restricted areas.
